CLAIM

The ornamental design for a circuit analyzer with surge protection as shown and described.

DESCRIPTION

FIG. 1 is a front perspective view showing my new design; FIG. 2 is a back perspective view showing my new design; FIG. 3 is a right side view thereof; FIG. 4 is a left side view thereof; FIG. 5 is a front view thereof; FIG. 6 is a back view thereof; FIG. 7 is a top view thereof; and, FIG. 8 is a bottom view thereof.
The broken lines shown in the figures illustrate portions of the circuit analyzer with surge protection that do not form any part of the claimed design.
